ALARM SYSTEM CABINET

David G. Barleen, Lafayette, Roger L. Ridings, Walnut Creek, and Theodore O. Pollard, Mountain View, Calif., assignors to Emergency Products Corporation, Parsippany, N.J.

Filed Dec. 23, 1974, Ser. No. 535,512

Term of patent 14 years

Int. Cl. D10—05

U.S. Cl. D10—106

FIG-1

FIG-3

FIG-2

FIG-5

FIG-4

FIG. 1 is an isometric view of an alarm system cabinet embodying our new design.

FIG. 2 is a front elevational view of the alarm system cabinet shown in FIG. 1.

FIG. 3 is a left side elevational view of the alarm system cabinet shown in FIG. 1.

FIG. 4 is a bottom plan view of the alarm system cabinet shown in FIG. 1.

FIG. 5 is a rear elevational view of the alarm system cabinet shown in FIG. 1.

We claim:

The ornamental design for an alarm system cabinet, as shown.
